PIPE CUTTER

Arthur S. Cann, Milford, Conn.

Application November 19, 1949, Serial No. 6,143

Term of patent 14 years

(Cl. D54—13)

To all whom it may concern:

Be it known that I, Arthur S. Cann, a citizen of the United States, residing at Milford, in the county of New Haven and State of Connecticut, have invented a new, original, and ornamental Design for Pipe Cutter, of which the following is a specification, reference being had to the accompanying drawing, forming a part hereof.

Fig. 1 is a side elevational view of a pipe cutter, showing my new design;

Fig. 2 is a top plan view;

Fig. 3 is a perspective view; and

Fig. 4 is a perspective view opposite the view of Fig. 3.

I claim:

The ornamental design for a pipe cutter, substantially as shown.

ARTHUR S. CANN.
